UNITED STATES PATENT OFFICE.

JOSEPH BOTT AND CHARLES F. MITCHEL, OF ROCHESTER, NEW YORK, ASSIGNEES TO
BASTIAN BROS. COMPANY, OF ROCHESTER, NEW YORK, A CORPORATION OF NEW
YORK.

MEANS FOR UNITING TWO PARTS.

Application filed December 6, 1923. Serial No. 679,030.

To all whom it may concern:

Be it known that we, JOSEPH BOTT and CHARLES F. MITCHEL, citizens of the United States, and residents of Rochester, in the 5 county of Monroe and State of New York, have invented certain new and useful Improvements in Means for Uniting Two Parts, of which the following is a specification.

10 The present invention relates to means for uniting two parts and particularly two parts in which one of them has an opening with a cylindrical wall, an object of this invention being to provide a novel 15 means on the other part for fitting it within the opening and engaging with such cylindrical wall in a manner to prevent the accidental separation of the two parts.

To these and other ends, the invention 20 consists of certain parts and combinations of parts, all of which will be hereinafter described: the novel features being pointed out in the appended claims.

In the drawings:

25 Fig. 1 is a sectional view through the two parts united;
Fig. 2 is a plan view of one of the parts;
Fig. 3 is a side view of the same part; and
Fig. 4 is a side view of another embodiment 30 of the invention.

In the illustrated embodiment of the invention, one of the parts indicated at 1 is in the form of a radiator of an automobile and the other part indicated at 2 is in the 35 form of a name plate. The radiator, in this instance, has an opening formed with a surrounding flange 3 bent inwardly to provide an internal cylindrical wall. The name plate has a flange 4 adapted to fit 40 snugly within the opening and to frictionally engage the internal cylindrical wall of the flange 3. In this instance, the annular flange 4 is formed from a cup-shaped member soldered or otherwise secured to the 45 rear face of the name plate.

The feature of this invention is the provision of a novel means for preventing the withdrawal of the flange 4 from the opening 3. In this instance, this means is in 50 the form of two oppositely extending spring arms 5 formed preferably from a single piece or strip of sheet steel and secured at 6 at a central point within the flange 4,

the cup-shaped member, in this instance, having a pressed up boss 7 to which the 55 strip of spring steel is secured. In order that the pressed up boss will not collect any great amount of solder beneath the same, the cup-shaped member has radial 60 grooves 8 formed on its under side to permit the flow of solder from the central boss. The spring arms 5 project outwardly beyond the perimeter of the flange 4 and are curved to conform to the perimeter of such flange. In order to permit this projection, the 65 flange 4 may be cut away from its outer edge, as shown at 9 in Fig. 3, at diametrically opposite points or the flange may be merely cut away to provide openings 9^a, as 70 shown in Fig. 4, the openings in both forms being sufficient to permit the inward movement of the gripping arms 5.

In uniting the parts, the flange 4 of the 75 part 2 is fitted in the opening of the part 1 and, in being forced in, causes the arms 5 to flex or bend toward the part 2, the latter being moved until it abuts the part 1. The arms 5 tend to prevent the accidental separation of the part 2 from the 80 part 1, due to the fact that any movement of the part 2 away from the part 1 tends to straighten the arms 5 and force them into binding engagement with the cylindrical internal wall of the flange 3, thus locking 85 the part 2 to the part 1.

What we claim as our invention and desire to secure by Letters Patent is:

1. In combination with two members to be united, one of which is provided with an opening with a cylindrical wall, and the other of which has a cylindrical flange fitted in said opening, spring arms extending through said flange from a point within the latter to cooperate with the cylindrical wall in order to have binding engagement with the latter.

2. In combination with two members to be united, one of which has an opening with a cylindrical wall and the other of which has a cylindrical flange fitting said opening, a strip of spring material secured within said flange and extending in opposite directions through the flange to enter into binding engagement with the cylindrical wall of the opening.

3. The combination with a member hav-

ing an opening provided with a cylindrical flange about the same, and a second member, of a cup-shaped member secured to said second member and fitting the interior wall 5 of said flange, and spring arms secured within said cup-shaped member and extending through the walls thereof to cooperate with the interior wall of the flange.

4. The combination with a member having an opening with a cylindrical wall, of a member having a flange fitting said cylindrical wall and provided with openings in opposite walls thereof, and a pair of oppositely extending spring arms arranged 15 within said flange and extending through

said openings to cooperate with a wall of the opening.

5. The combination with a member having an opening with a cylindrical wall and a second member, of a cup-shaped member arranged in the second member and having a central boss and also openings in the sides of said cup shaped member, and a spring strip secured between its ends to the boss and extending through such openings to cooperate with the interior wall of the opening in the first named member.

JOSEPH BOTT.
CHARLES F. MITCHEL.
